UNITED STATES PATENT OFFICE.

JAMES T. HOLLAND, OF SAYRE, OKLAHOMA.

CULTIVATOR.

1,161,674.

Specification of Letters Patent.

Patented Nov. 23, 1915.

Application filed November 21, 1914. Serial No. 873,318.

To all whom it may concern:

Be it known that I, JAMES T. HOLLAND, a citizen of the United States, residing at Sayre, in the county of Beckham and State 5 of Oklahoma, have invented new and useful Improvements in Cultivators, of which the following is a specification.

This invention relates to machines or devices for tilling and cultivating the soil, 10 and the prime object of the invention is to produce a simple and improved frame structure which may be used for supporting earth engaging tools of various descriptions and which may, itself, be manipulated to present the supporting frame, as well as the tools in various positions according to the character of the work that is to be performed.

A further object of the invention is to 20 produce frame units of a simple and improved construction which may be readily assembled together and with the tools that are to be utilized.

A further object of the invention is to 25 simplify and improve the frame structure and adjusting mechanism.

With these and other ends in view which will readily appear as the nature of the invention is better understood, the same consists in the improved construction and novel 30 arrangement and combination of parts which will be hereinafter fully described and particularly pointed out in the claims.

In the accompanying drawings has been 35 illustrated a simple and preferred form of the invention, it being, however, understood that no limitation is necessarily made to the precise structural details therein exhibited, but that changes, alterations and modifications 40 within the scope of the claims may be resorted to when desired.

In the drawings, Figure 1 is a top plan view of a machine constructed in accordance with the invention, showing a simple and preferable arrangement of the same. Fig. 2 is a longitudinal vertical sectional view taken on the line 2-2 in Fig. 1. Fig. 3 is a longitudinal sectional view similar to Fig. 2, but showing a different adjustment of the parts. 50 Fig. 4 is a perspective detail view showing the forward end of one of the frame units or runners. Fig. 5 is a perspective detail view showing one end of another slightly modified frame unit or runner. Fig. 6 is a 55 perspective detail view of one of the shoes

used in connection with the frame units or runners. Figs. 7 and 7^a are perspective detail views showing two forms of stop members used in connection with the runners and the earth engaging tools. Fig. 8 is a perspective detail view showing one end of one of the frame units slightly tilted to disclose the bottom side thereof. Fig. 9 is a perspective detail view of one of the triangular cutting blades used in connection with the frame units. Figs. 10 and 11 are detail views showing two forms of plows that may be used in connection with the device. Fig. 12 is a sectional detail view taken on the line 12-12 in Fig. 3. Fig. 13 is a detail view partly in section and partly in elevation of one of the adjusting sleeves and the limb on which it is mounted. Fig. 14 is a top plan view of the seat support. Fig. 15 is a detail plan view of one of the 70 adjusting plates connected with the guide arms. Figs. 16, 17 and 18 are sectional detail views taken on the lines 16-16, 17-17 and 18-18, respectively, in Fig. 15. Fig. 19 is a diagrammatic detail view showing 75 the device arranged for cultivating a row of plants growing at the crest of a ridge. Fig. 20 is a diagrammatic detail view showing the device arranged for cultivating a row of plants growing in a furrow. Fig. 80 21 is a detail view in sectional elevation showing a portion of the frame equipped with disks in place of the plows illustrated in the previous figures. Fig. 22 is a detail view partly in plan and partly in section 90 showing a portion of the frame and a disk carried thereby, the disk being shown in section. Fig. 23 is a detail plan view showing a small portion of the frame when the machine is used as a harrow. Fig. 24 is a sectional detail view taken on the line 24-24 in Fig. 23. Fig. 25 is a detail view showing a form of a harrow tooth which may be employed. Fig. 26 is a detail plan view partly in section, showing a portion of the frame structure slightly modified to enable the adoption of a different arrangement of the frame units. Fig. 27 is a plan view illustrating a different arrangement of frame units. Fig. 28 is a perspective detail view showing one 100 of the frame sections provided with handles whereby it may be guided.

Corresponding parts in the several figures are denoted by like characters of reference.

In its most simple and preferred form the 110

improved machine is composed of two sections, each made up of a plurality of frame units or runners A which are mounted for operation on connecting rods B, each of which is provided at its inner end with an upstanding limb 15.

The frame units or runners, as shown in detail in Figs. 4, 5 and 8 are provided with a longitudinal vertical slot 16 extending almost through the entire length thereof. While no limitation to the precise manner of manufacture is intended, each runner may be made up of two bars or plates of suitable dimensions welded together, or otherwise connected at the ends thereof and spread or spaced apart between the connected portions, the ends being subsequently trimmed, as shown in Figs. 4 and 5. The point 17 shown in Fig. 4 is produced by beveling the top and the two sides of the runner, the apex 18 of the point being thus disposed midway between the planes of the two side faces of the runner. The point 19 shown in Fig. 5 is produced by beveling the top face and one side face of the runner, so that the apex 20 of the point will be located in the intersection of the points of the bottom face and one side face of the runner. In the construction of each section 30 of the implement a plurality of runners is employed, as best seen in Fig. 1, where each section has been shown as including four runners, the number of which, however, may be varied. Of the runners of each section 35 the two outermost ones are to be provided with points trimmed substantially as seen in Fig. 5, with the reservation that the outer side wall of each of said outermost runners is left untrimmed and presented at right angles to the bottom face. The intermediate runners of each section have their points 40 trimmed, as seen in Fig. 4. By this arrangement the points of the runners of each section will constitute a comb, the terminal 45 points of which are located in the planes of the side faces of the runners, thus enabling a swath of weeds and the like to be gathered, the width of which is equal to the extreme width of the runner section. The 50 two runner sections are identical in construction and, the runners being pointed at both ends, they may be reversed end for end, or the implement may be arranged to be used with either end foremost.

55 For the protection of the runners I prefer that they be shod with wear plates of steel or other suitable material. The shoe, a specimen of which may be seen in Fig. 6, comprises a socket 21 adapted to receive the 60 point of the runner to which it is applied and provided with two rearwardly extending bars 22 adapted to engage the under faces of the side members of the runner. A separate shoe is applied to each end of the runner, and the bars 22 are recessed at the

ends thereof, as seen at 23, to form lap-joints. The bars are bolted or otherwise secured to the under faces of the runners which are thus enabled to resist wear. It is also obvious that the shoes when worn out 70 may be renewed at less expense than would be incurred in providing entire new runners.

Each runner may be provided at either or both ends with cutting blades 24, one of which is shown in detail in Fig. 9, by reference to which it will be seen that said blades are of triangular shape and provided with apertures 25 for the passage of screws whereby said blades may be secured either to the bottom or side faces of the two points of the runners. The blades 24 are of a width materially exceeding the width of the runner faces on which they are mounted so that they will serve to effectively cut or dig into the soil. It is obvious that the bottom and side faces of the runner points are to be provided with sockets for the reception of the fastening members, such sockets being indicated at 26 in Figs. 4, 5 and 8. The sockets 21 of the shoes are to be provided with apertures 27 alining with the sockets 26.

The runners of each runner section are spaced apart on the rods B, and spacing means of various kinds may be employed. Thus, for instance, the runners may be spaced apart by means of plow blades, as seen in Figs. 1, 2 and 3. Said plow blades may either be provided with square cutting edges, as seen in Fig. 10, where a specimen of such a blade is shown designated by 27', or said blades may each have a cutting edge lying at an angle to the length thereof, as seen in Fig. 11, where a specimen of a pointed blade is shown designated by 28. 100 In either case, however, the blades should have straight and parallel side edges and be of a suitable width to properly space apart the runners between which they are mounted. Each blade is provided with a plurality of preferably countersunk apertures 29 for the reception of a fastening member, such as a screw 30', whereby it is secured in position on one of the cross bars B. In Figs. 22, 23 spacing sleeves 30 have been shown, and these spacing sleeves may be apertured for the reception of the shanks of harrow teeth, shown at 31, it being obvious that the rod B must be correspondingly apertured for the passage of the shank of the harrow tooth. It will be obvious that the runner at one side of each runner section will abut on the upstanding limbs 15 and that such runner, together with the intermediate runners, will be held securely against lateral 115 displacement by the spacing members placed on the rods B. For the purpose of securing the runner in position at the opposite or outermost end of each runner section, nuts 32 are employed, said nuts being located 120

within the slots 16 of the outermost runners, and thus serving to securely assemble the runner sections without leaving external projections on the outermost runners which would be disadvantageous in affording places of lodgment for weeds, grass roots and the like which eventually interfere with the progress of the machine.

When spacing sleeves are used, as seen at 10 in Fig. 22, said spacing sleeves may be used to support revoluble disks, as indicated at 33, such disks being obviously placed in position during the process of assembling the parts of the runner sections. 15 When plow blades, such as 27' or 28 are used, (they may be applied to the rearward, as well as the forward, cross bars or rods B. When applied to the rearward rods the said blades may, however, be reversed, as indicated in dotted lines in Fig. 2, so as to drag over the ground and thus constitute gage plates whereby the rearward end of the machine is supported in a relatively elevated position. Gage wheels, as shown at 34, may 25 also be employed, such gage wheels being arranged in the slots 16 of the end runners of each section, as seen in Fig. 1, where the intermediate runners have been shown as being equipped with cutting disks 35, which 30 latter, like the gage wheels, are mounted for rotation on bolts 36 passing transversely through the runners.

For the purpose of supporting the plow blades 27 or 28 at the desired inclination, 35 stop members consisting of rods may be employed, one of such rods having been shown in detail in Fig. 7, where it is designated at 37. The several runners are each provided with a series of apertures 38 through which 40 the rods 37 may be strung, said rods being secured by means of cotter pins 39. In place of the rods stop members consisting of short screws 40 may be engaged with the apertures 38, which latter in such event should 45 be appropriately threaded. By providing a sufficient number of appropriately arranged apertures 38 it is obvious that the supporting members whether consisting of rods or screws may be arranged in such fashion as 50 to support the plow blades at the desired inclination.

The upper extremities of the limbs 15 are reduced, forming near the upper end of each limb a shoulder, as seen at 41, see Figs. 16, 55 17 and 18, the reduced portion of each limb being also provided with an annular groove 42.

43 designates a seat support which consists of a bar or strip of steel having a central aperture 44 for the passage of a fastening member, such as a bolt 45, whereby the seat 46 may be mounted in position. At either side of the central perforation 44 are three rows of apertures 47, 48, 49. The perforations of one row, 47, at opposite sides of

the central perforation are inclined downwardly and outwardly; the perforations 48 are vertically disposed and the perforations 49 at opposite sides of the center are inclined downwardly and inwardly. The seat support 43 is mounted on the upper ends of the limbs 15 at the rearward end of the machine, and it will be seen that said limbs will be maintained in a vertical position and are also capable of being tilted outwardly 75 or inwardly, according to which perforations they are placed in engagement with, it being understood that the perforations are of a diameter equal to the reduced upper ends of the limbs. Thus, when the reduced ends of the limbs are placed in the straight perforations 48, the limbs will be maintained in a vertical position, and the runner supporting rods will be maintained in a horizontal position, while by shifting 80 the limbs to the perforations 47 or 49, the limbs may be tilted downwardly and outwardly or downwardly and inwardly, as may be desired, thus producing the effects illustrated diagrammatically in Figs. 20 and 90 19, respectively, and producing an implement which will be adapted to operate in a furrow or on a ridge, as may be required. It is obvious that in neither case the reduced ends of the limbs 15 need be subjected to 95 unusual strain, since the actual weight of the implement will be supported on the ground to the contour of which the implement is adapted. A plurality of perforations is provided in each row in order that 100 provision may be made for variously spacing the runner sections. The parts may be assembled by means of set screws 50 threaded into the seat support and engaging the annular grooves in the reduced portions of the limbs 15. For the purpose of connecting together the upstanding limbs at the forward ends of the runner sections, guide bars 51 are provided, said guide bars being provided with rows of apertures 52 for the passage 105 of a bolt 53 whereby said guide bars are pivotally connected. Each of the guide bars is provided at its forward end with a downwardly extending offset 54 carrying at its lower extremity a forwardly projected 110 plate or bracket 55 having three perforations, two of which, 56, 57, are inclined in opposite directions, see Figs. 15, 17 and 18, while the third perforation, 58, is vertical, see Figs. 15 and 16. The reduced upper ends 115 of the limbs 15 at the forward ends of the runner sections may be engaged with either of these perforations corresponding with the perforations in the seat support with which the reduced upper ends of the limbs 120 at the rearward ends of the runner sections are engaged. The forward limbs will thus be supported in a position corresponding with that of the rearward limbs, and the parts of the device will thus be assembled 125 130

in a secure manner, it being understood that set screws 59, threaded through the brackets 55 will be utilized to engage the annular grooves in the reduced upper ends of the forward limbs for the purpose of assembling the parts. By utilizing the rearward ends of the guide bars 51 as handles, said guide bars may be moved about the axis of the pivot 53, thereby varying the distance between the forward ends of the runner sections. This operation may be readily performed by the operator who occupies the seat in rear of the guide bars. Let it be understood, however, that if desired the seat support may be mounted on the limbs at the forward end of the implement and the guide bars on the limbs at the rearward end in which event, however, the service of a second person walking behind the implement would be needed for the purpose of manipulating the guide bars.

The forward and rearward limbs 15 of each runner section are connected together by parallel bars 60, see Figs. 2, 3 and 12, said bars being connected to the limbs by pivot bolts 61 having eyes 62 with which latch hooks 63 are pivotally connected, said latch hooks being adapted to engage apertures 64 in the runners. It will be seen that by disengaging the latch hooks the upstanding limbs may be manipulated so as to tilt the rods B about their respective axes, thereby varying the inclination of the plow blades carried on said rods, it being understood that if the forward ends of the plow blades are to be swung downwardly, the supporting members 37 or 40 must be previously removed. Auxiliary supporting means for the upstanding limbs are provided, the same consisting of sleeves 65 fitted on the limbs and abutting at their lower ends on the upper edges of the runners nearest the upstanding limbs. The sleeves 65 are pressed downward by the action of springs 66, coiled about the limbs 15 between said sleeves and the bolts 61. Each sleeve has a lug 67 engaging between two of a plurality of teeth 68 fixed on the top edge of the runner. Each sleeve is also provided with a pin 69 engaging a bayonet slot 70 in the limb 15 for the purpose of maintaining the sleeve in retracted position when desired. Each sleeve carries an angle plate 71, the lower extremity of which may constitute the stud 67, and the upper laterally extending portion of which, designated by 72, will constitute a foot rest and will at the same time form a handle whereby the sleeve may be readily retracted against the tension of the spring 66 for the purpose of disengaging the stud 67 from the lugs 68 and thus permit the rod B to be rocked or oscillated.

It is to be understood that the retaining means consisting of vertically movable sleeves, the studs associated therewith and

the teeth engaged by said studs are to be so arranged and proportioned with respect to the supporting devices 37 or 40 of the plow blades 27, 28 that when the rods B are rocked to vary the inclination of the plow blades and the latter engage the supporting means provided, the lugs or studs 67 associated with the sleeves will then engage between two of the rack teeth 68. It follows that when three positions of the plow blades are provided for, four properly spaced rack teeth will be necessary. The latch hooks 63 are not needed unless it shall be desired to throw the plow blades entirely clear of the ground, as indicated in dotted lines in Fig. 3.

For the purpose of applying draft to the improved implement clevises, indicated at 73, see Figs. 2 and 3, are mounted on the bolts 36 by which the gage wheels 34 are connected with the end runners of each section. Mounted on the runners in front of said bolts are upstanding brackets 74, each of said brackets being provided with a plurality of apertures 75 for the passage of the shank of a draft hook 76, the hook portion of which, 77, is connected with the clevis. The bracket 74 is pivotally connected with the runner, and it follows that by transferring the shank 76 from one to another of the apertures 75 the tilt or inclination of the clevis 73 and the bracket 74 may be varied, thus raising or lowering the point of attachment of the draft.

In Figs. 26 and 27 there has been shown diagrammatically an arrangement whereby each of the runners is provided with inclined apertures 78 through which the connecting rods B may be passed when desired, thereby affording an arrangement whereby the runner will be disposed in step-by-step formation, one runner in advance of the next preceding runner. This arrangement may sometimes be advantageously adopted. In Fig. 28 a single runner section has been shown equipped with an evener 79 for the attachment of draft and with handles 80 whereby it may be guided. The runner sections are thus capable of being independently used.

From the foregoing description, taken in connection with the drawings hereto annexed, the construction and operation of this invention will be readily understood. When the implement is drawn over the ground, the plow blades will cut or dig into the ground and operate in a manner very similar to the operation of an ordinary wooden plane by taking slices or shavings from the ground which will then be dumped between the runners and thoroughly broken up. It is evident that the improved implement is capable of a large variety of uses and that the component parts may be variously arranged for operation in such manner as may be preferred.

Having thus described the invention, what is claimed as new, is:—

1. In a cultivating implement, a runner unit having a flat bottom face, pointed ends and a vertical slot extending longitudinally therethrough, in combination with a protective casing comprising sockets for the reception of the points, bars extending from said sockets and having terminal recesses combining to form lap-joints, and means for securing the bars on the underside of the runner.
2. In a cultivating implement, a runner unit having pointed ends and a vertical slot extending longitudinally therethrough, triangular cutting blades of a width materially exceeding that of the runner, and means whereby the blade is secured on the point of the runner to provide an earth engaging cutting edge.
3. In a cultivating implement, a runner section comprising a pair of rods, each having an upstanding limb at one end and a plurality of runner units, each having pointed ends, a longitudinal vertical slot, and transverse apertures engaging the rods, and means whereby the runner units are spaced and retained on the rods.
4. A runner section comprising two rods each having an upstanding limb at one end, a plurality of longitudinally slotted runner units having transverse apertures engaging the rods, spacing members interposed between the runner units, and nuts threaded on the ends of the rods and engaging the slot in the outermost runner unit to retain the runner units in position and leave no projection beyond the side face of the outermost runner unit.
5. A runner section comprising two rods each having an upstanding limb at one end, runner units having transverse apertures engaging the rods, plow blades mounted on the rods between the runner units to space the latter apart, and means for retaining the outermost runner unit on the rods.
6. A runner section comprising a plurality of terminally pointed runner units, rods extending transversely through said units and capable of rocking movement therein, and plow blades mounted on the rods between the runner units to space the latter apart, said plow-blades partaking of the rocking movement of the rods.
7. A runner section comprising a plurality of terminally pointed runner units, rods extending transversely therethrough and having upstanding limbs at one end, said rods being capable of rocking movement with respect to the runner units, plows mounted on the rods to space the units apart, said plows partaking of the rocking movement of the rods, and a bar pivotally connected with the upstanding limbs of the rods, said bar being parallel with the runner units.
8. A runner section comprising a plurality of terminally pointed runner units each having a vertical slot extending longitudinally therethrough, rods extending transversely through the runner units, each having an upstanding limb at one end, means for spacing and assembling the runner units on the rods, and earth engaging implements supported for rotation in the slots of the runner units.
9. A pair of runner sections, each comprising a plurality of runner units, rods extending transversely therethrough and upstanding limbs at the inner ends of said rods, a seat support mounted on the upper ends of one pair of limbs, and pivotally connected guide bars mounted on the upper ends of another pair of limbs.
10. A pair of runner sections, each comprising a plurality of runner units, rods extending transversely therethrough and upstanding limbs at the inner ends of said rods, a seat support mounted on the upper ends of one pair of limbs, pivotally connected guide bars mounted on the upper ends of another pair of limbs, and a bar pivotally connected with the upstanding limbs of each section, said bar being parallel with the runner units.
11. In a cultivating implement, a pair of runner sections each comprising a plurality of runner units, rods extending transversely therethrough and having rocking movement therein, and upstanding limbs at the inner ends of the rods of the respective sections, a bar pivotally connected with the upstanding limbs of each section, and means connected with the upper ends of the limbs of the respective sections to assemble said sections together, said means being adapted to support the limbs at various inclinations with respect to the surface of the ground.
12. A pair of runner sections, each comprising a plurality of runners, a rod extending transversely therethrough and upstanding limbs at the inner ends of said rods, said limbs being terminally reduced at their upper ends, in combination with a seat support having a plurality of apertures extending therethrough at various inclinations with respect to the surface thereof, some of said apertures being engaged with the upper ends of an upstanding limb pertaining to each runner section.
13. A runner section comprising a plurality of runners, rods extending transversely therethrough, upstanding limbs at one end of said rods, and a bar pivotally connecting said limbs, a sleeve mounted on one of the upstanding limbs and overhanging the nearest runner unit, rack teeth associated with said last mentioned runner unit, a bar carried by the sleeve and having at its lower end a lug engaging the rack teeth, and at its upper end a foot rest whereby it may be

manipulated, and a spring exerting pressure on the sleeve in the direction of the rack teeth.

14. A runner section comprising a plurality of runners, rods extending transversely therethrough, upstanding limbs at one end of said rods, and a bar pivotally connecting said limbs, a sleeve mounted on one of the upstanding limbs and overhanging the nearest runner unit, rack teeth associated with the last mentioned runner unit, a bar carried by the sleeve and having at its lower end a lug engaging the rack teeth, and at its upper end a foot rest whereby it may be manipulated, a spring exerting pressure on the sleeve in the direction of the rack teeth, and means whereby the sleeve may be secured in retracted position against the tension of the spring.
15. In a cultivating implement, a pair of runner sections, each comprising a plurality of runner units, rods extending transversely therethrough for rocking movement therein, upstanding limbs at the inner ends of said rods, bars pivotally connecting the upstanding limbs of the respective runner sections, and plow blades interposed between the runner units, secured on the rocking bars and partaking of the movement thereof, a seat support mounted on two upstanding limbs pertaining to the two runner sections, guide bars mounted on the other two upstanding limbs pertaining to the two runner sections, means whereby the guide bars are pivotally connected together, and means for securing the upstanding limbs in various positions to which they may be tilted with respect to the runners, in combination with means whereby the plow blades may be independently supported with respect to the runners in various positions to which they may be tilted by the rocking movement of the rods whereon they are mounted.
16. In a cultivating implement, a pair of runner sections, each comprising a plurality of runner units, rods extending transversely therethrough for rocking movement therein, upstanding limbs at the inner ends of said rods, bars pivotally connecting the upstanding limbs of the respective runner sections, and plow blades interposed between the runner units, secured on the rocking bars and partaking of the movement thereof, a seat support mounted on two upstanding limbs pertaining to the two runner sections, guide bars mounted on the other two upstanding limbs pertaining to the two runner sections, means whereby the guide bars are pivotally connected together, and means for securing the upstanding limbs in various positions to which they may be tilted with respect to the runners, in combination with means whereby the plow blades may be independently supported with respect to the runners in various positions to which they may be tilted by the rocking movement of the rods whereon they are mounted.

connected together, and means for securing the upstanding limbs in various positions to which they may be tilted with respect to the runners.

17. In a cultivating implement, a pair of runner sections, each comprising a plurality of runner units, rods extending transversely therethrough for rocking movement therein, upstanding limbs at the inner ends of said rods, bars pivotally connecting the upstanding limbs of the respective runner sections, and plow blades interposed between the runner units, secured on the rocking bars and partaking of the movement thereof, a seat support mounted on two upstanding limbs pertaining to the two runner sections, guide bars mounted on the other two upstanding limbs pertaining to the two runner sections, means whereby the guide bars are pivotally connected together, and means for securing the upstanding limbs in various positions to which they may be tilted with respect to the runners, in combination with means whereby the plow blades may be independently supported with respect to the runners in various positions to which they may be tilted by the rocking movement of the rods whereon they are mounted.

In testimony whereof I affix my signature in presence of two witnesses.

JAMES T. HOLLAND.
